United States Patent

Des. 234,478
Patented Mar. 18, 1975

234,478

SIDE ARM CHAIR

Earl H. Koepke, Rte. 1, Scenic Drive,
Sturgis, Mich. 49091

Filed Dec. 13, 1972, Ser. No. 314,605

Term of patent 14 years

Int. Cl. D6—01

U.S. Cl. D6—56

FIG. 1

FIG. 2

FIG. 3

FIG. 4

FIG. 5

FIG. 1 is a top view of a first embodiment of a side arm chair according to the invention;

FIG. 2 is a front view of a first embodiment of a side arm chair according to the invention;

FIG. 3 is a front, side prospective view of a first embodiment of a side arm chair according to the invention;

FIG. 4 is in side perspective thereof; and

FIG. 5 is a view in side perspective of a second embodiment of a side arm chair according to the invention.

The undisclosed portion of the backrest is plain and unornamented.

I claim:

The ornamental design for a side arm chair, substantially as shown and described.
